UNITED STATES PATENT OFFICE.

FRANK B. STILLWELL, OF LUDINGTON, MICHIGAN, ASSIGNOR OF ONE-HALF TO LEO
STILLWELL, OF LUDINGTON, MICHIGAN.

SLIDING BOLT.

1,056,228.

Specification of Letters Patent. Patented Mar. 18, 1913.

Application filed March 23, 1911. Serial No. 616,488.

To all whom it may concern:

Be it known that I, FRANK B. STILLWELL, a citizen of the United States, residing at Ludington, in the county of Mason, State 5 of Michigan, have invented certain new and useful Improvements in Sliding Bolts, of which the following is a specification.

This invention relates to improvements in sliding bolts.

10 The main objects of this invention are first, to provide an improved sliding bolt, which is adapted to clamp the door or lid, that is apply pressure thereto when the bolt is shot. Second: To provide an improved 15 sliding bolt embodying these advantages, which is reversible in that it may be applied either to the door or to the casing as may be desired. Third: To provide an improved sliding bolt, which is simple and 20 economical in structure and easily applied.

Further objects, and objects relating to structural details, will definitely appear from the detailed description to follow.

I accomplish the objects of my invention 25 by the devices and means described in the following specification.

The invention is clearly defined and pointed out in the claims.

A structure which is a preferred embodiment 30 of my invention is clearly illustrated in the accompanying drawing, forming a part of this specification, in which:

Figure I is a detail perspective view of a structure embodying the features of my invention. Fig. II is a plan view of the structure appearing in Fig. I, with a portion of the casing broken away. Fig. III is a detail longitudinal section, taken on a line corresponding to the broken line 3—3 40 of Fig. II. Fig. IV is a transverse section, taken on a line corresponding to 4—4 of Fig. II. Fig. V is a transverse section taken on a line corresponding to line 5—5 of Fig. II. Fig. VI is a detail longitudinal section 45 corresponding to that of Fig. III, with the parts reversed, that is the keeper is in this view mounted upon the door casing and the bolt on the door, whereas in the other figures the keeper is mounted on the door and the bolt on the door casing.

In the drawings, similar reference characters refer to similar parts throughout the several views, and the sectional views are

taken looking in the direction of the little arrows at the ends of the section lines.

55

Referring to the drawing, 1 represents a door and 2 a door casing. The casing of my improved lock preferably consists of an outer member 3, having a chamber therein with lateral extensions at its rear end and 60 a back plate or member 4. These casing members are preferably formed of sheet metal, the member 3 being provided with attaching flange 3' at each side of the bolt chamber, the attaching screws 5, being arranged through these flanges and through the back plate, while the attaching screws 6 are arranged through the portions forming the extensions of the casing chamber. The plate 4 is flanged upwardly at its rear end 65 as at 7, there being a slot like opening between the casing members through which the lever 8 is arranged. The lever 8 is provided with diverging pivot ears 9 at its inner end, one of the attaching screws 6 being arranged through one of the ears, the other ear being arranged in a slot 10, in the rear end of the bolt 11 and being secured to the bolt by means of the pivot 12. The pivot 12 is retained by the casing. The screws 6 70 are disposed equal distances from the center line of the casing, so that the lever 8 may be mounted on either screw as desired, the other ear being secured to the bolt. The bolt 11 is supported for longitudinal movement 75 in the chamber, the rear end of the bolt being tapered to permit a limited lateral movement on the actuation of the lever. This of course could be provided for by tapering the chamber, but I consider the 80 most practical way to be to taper the bolt as shown. The bolt is beveled at 13 to engage the keeper 14, which has an inclined bolt engaging portion 15.

85

The keeper is preferably struck up from 90 sheet metal, the bolt being adapted to coat with either the outer side of the engaging portion 15 of the keeper as shown in Figs. I to V inclusive, or its inner side as shown in Fig. VI, depending on the relation of the 95 bolt and keeper; that is whether the bolt is mounted upon the casing or upon the door. The structure is readily adapted for application in either relation, it being only necessary to turn the bolt over when it is 100 changed from one position to the other and

105

facing the keeper to correspond. I preferably arrange the lever so that it is in its down position when the bolt is retracted, so that the bolt is not likely to be projected by 5 jars or shocks, or to be accidentally projected. The bolt engaging the keeper with the cam or clamping action is subjected to sufficient friction so that it is not likely to be retracted, except through manual manipulation. 10 With the parts thus arranged the desired clamping action is secured in a simple light structure.

I preferably construct the casing of sheet metal as shown, although of course this does 15 not change the operation of the bolt. My improved sliding bolt is effective as a lock as well as in securing the clamping action. It is very easily operated, either to project or to retract the bolt.

20 I have illustrated and described my improvements in a simple embodiment thereof. I am aware that considerable variation and structural details are possible, but as such variation will no doubt suggest itself to 25 those skilled in the art to which this invention relates, I have not attempted to illustrate or describe the same herein.

Having thus described my invention, what 30 I claim as new and desire to secure by Letters Patent is:

1. In a sliding bolt, the combination with the casing, comprising a sheet metal outer casing member having a chamber with lateral extensions at its rear end and an attaching flange at each side of the chamber, a sheet metal back plate having an upturned flange at its rear end, there being a slot like lever opening between said casing members at their rear ends; a pair of casing attaching 35 screws adapted to act as lever pivots arranged through the extension portions of said casing chamber, a bolt having a beveled keeper engaging portion said bolt being tapered rearwardly to permit lateral movement, its rear end being slotted; a lever having 40 a pair of pivot ears, one ear being mounted on one of said attaching screws, the other ear being arranged in the slot of said bolt and pivotally secured thereto, said

bolt being reversible in said casing and a 50 sheet metal keeper having a struck up inclined bolt engaging portion.

2. In a sliding bolt, the combination with the casing having a bolt chamber provided with lateral extensions and a lever slot at 55 its rear end; a bolt provided with an inclined keeper engaging portion; a lever having a pair of pivot ears at its inner end arranged through said slot, one ear being pivotally secured to said bolt; lever pivots 60 arranged through said chamber extensions, said lever being adapted to be mounted on either of said pivots, said bolt being reversible in said casing to permit its beveled keeper engaging portion being faced in or 65 out; and a keeper having an inclined bolt engaging portion adapted to be reversed to permit the bolt to engage the inner or outer side thereof, whereby the bolt casing may be mounted upon the door and the keeper 70 upon the door casing or vice versa.

3. In a sliding bolt, the combination with the casing; a bolt provided with an inclined keeper engaging portion adapted to be reversed in said casing so that it may be faced 75 in or out; a pair of lever pivots arranged one at each side of the longitudinal center of the bolt; a lever having a pair of laterally projecting pivot ears, the pivot holes of the ears being uniformly spaced relative to the 80 longitudinal center of the lever, one ear being mounted on one of said pivots, the other being pivoted to said bolt, said lever being reversible by changing from one pivot to the other; and a keeper having an in- 85 clined bolt engaging portion adapted to be reversed so that the bolt engages the inner or the outer side thereof exerting an inward or outward pressure thereon, for the purpose specified. 90

In witness whereof, I have hereunto set my hand and seal in the presence of two witnesses.

FRANK B. STILLWELL. [L.S.]
